UNITED STATES PATENT OFFICE.

CHARLES ARCHIBALD STONEHILL, OF GLENCOE, ILLINOIS.

TOOTHBRUSH CONSTRUCTION.

Application filed September 8, 1923. Serial No. 661,633.

To all whom it may concern:

Be it known that I, CHARLES ARCHIBALD STONEHILL, a citizen of the United States, and a resident of Glencoe, in the county of Cook and State of Illinois, have invented a new and useful Improvement in Toothbrush Construction, of which the following is a full, clear, and exact description.

My invention relates to improvements in tooth brush constructions, and it consists in the combinations and arrangements herein described and claimed.

An object of my invention is to provide a tooth brush having in the handle thereof a tooth pick so disposed that the pick may be at any time withdrawn for use.

A further object of my invention is to provide a device of the type described in which the pick is so disposed as not to interfere with the use of the tooth brush proper.

Other objects and advantages will appear in the following specification, and the novel features of the invention will be particularly pointed out in the appended claim.

My invention is illustrated in the accompanying drawings forming part of this application, in which—

Figure 1 is a side view of a tooth brush constructed according to my invention, a portion of the brush being shown in section,

Figure 2 is a plan view of one end of the brush handle shown in Figure 1,

Figure 3 is an enlarged face view of the tooth pick,

Figure 4 is a view similar to Figure 2 showing a modified form,

Figure 5 is a view similar to Figure 2 showing another modified form, and

Figure 6 is a section along the line 6—6 of Figure 5.

In carrying out my invention I make use of a tooth brush having bristles 1 and the handle 2. The latter is designed to carry a tooth pick 3. This pick may be of any suitable material, such as wood, celluloid, shell, hard rubber, or the like. It is preferably provided with a head portion 4, and is pointed as shown in Figure 3.

The body portion of the handle is provided with a slot 5 extending inwardly from one end thereof. In Figures 1 and 2 this slot is shown as being disposed substantially along the central axis of the handle, that is, midway between the sides and midway between the upper and lower edges. The head 4 limits the movement of the tooth pick in the slot.

In Figure 4 I have shown the tooth pick as being carried on one side of the central line so as to provide for an opening 6 by means of which the tooth brush may be hung on a hook.

In Figure 5, which is a modified form, a slot 7 is shown running from the end of the handle toward the brush. This slot is T-shaped in cross section as is shown in Figure 6 so that the tooth pick 3 when placed thereon is seen from above.

In each of the forms the tooth brush will have with it at all times the tooth pick so that the thorough cleansing of the teeth can be accomplished by the pick and the brush after which the pick can be cleansed, and then replaced in the slot in the handle, where it will remain.

The head 4 not only limits the movement of the tooth pick into the slot, but it provides a means for readily pulling out the tooth pick.

I claim:

A tooth brush construction comprising a curved handle having a slot in one end thereof, the longitudinal axis of said slot being curved in conformity with the curvature of the handle, and a curved tooth pick arranged to slidably enter the slot and to frictionally engage with the walls of the slot so as to normally be held in place, said tooth pick having a head provided with a shoulder arranged to engage with the end of the handle and to limit the movement of the tooth pick inwardly, said head being of less width than the width of the handle, whereby the head is rendered inconspicuous.

CHARLES ARCHIBALD STONEHILL.
